TRACTION SPLINT HITCH

Edgar Ellis, Lorain, Ohio

Application March 31, 1938, Serial No. 199,166

6 Claims. (Cl. 128—84)

This invention relates to splints employed in supporting fractured bones, and more particularly to a traction type splint primarily adapted for emergency use and adjustable for use on either a fractured leg or arm of varying size and length.

It frequently happens that in transporting a person who has received a bone fracture from the scene of the accident that the injury is severely aggravated due to the bone fragments being jolted and it is commonly recommended that an injured person be not disturbed until competent help arrives. It has heretofore been common practice to provide a splint for a broken arm or leg consisting of rigid elements disposed longitudinally along the leg or arm and held in place by bandaging or similar material. However, a splint of this type tending to hold the fractured portions of the bone in alignment, does not effectively prevent relative movement of the bone portions longitudinally of the splint, resulting in contact of the bone fractured portions and consequent aggravation of the injury.

It has also heretofore been proposed to provide splints commonly known as traction splints wherein a rigid member is extended outwardly beyond the fractured leg or arm and a hitch is applied to the wrist or ankle to exert tension maintaining the fractured portions of the bone in proper relation for knitting. However, prior splints of this type with which I am familiar are intended to be applied at the hospital or the like and require considerable time to adjust in addition to requiring that the fractured member be suspended in such manner that a weight may hang from the splint to exert proper tension.

It is extremely important that the fractured bone portions be maintained under tension during transportation to the hospital or the like but since in answering a call to the scene of an accident, it may be found that either a leg or arm is fractured and that the injured person may be either a child or an adult, a considerable number of splints would have to be stored in the ambulance to meet the varying conditions encountered. Due to the other emergency equipment necessarily carried, it is desirable that a minimum amount of room be required for the storage of splints, in an ambulance.

I have devised a traction splint which is quickly adjustable for adaptation to either a fractured arm or a fractured leg and which is suitable for either an adult or a child. I have further provided an improved, easily applied hitch for securing to the wrist or ankle whereby the proper tension may be exerted on the fractured member.

It is an object of my invention, therefore, to provide an improved traction-type splint primarily adapted for emergency use when transporting an injured party to a hospital or the like.

Another object of my invention is to provide an improved traction-type splint which is adjustable to support either a fractured leg or arm of an adult or a child.

Another object of my invention is to provide a traction splint having improved hitch means for the ankle or wrist associated therewith.

Another object of my invention is to provide an improved traction splint having longitudinally extending support members adapted to be maintained in alignment with the bone of the arm or leg.

Another object of my invention is to provide a splint of the above type which has no tendency to impart a twist to the fractured arm or leg.

Other objects of my invention and the invention itself will become increasingly apparent from a consideration of the following description and drawings wherein:

Fig. 1 is an elevational view of my improved splint applied to a leg;

Fig. 2 is an elevational view of the splint of Fig. 1 applied to an arm;

Fig. 3 is a side elevational view of the leg supporting splint of Fig. 1;

Fig. 4 is a side elevational view of the arm supporting splint of Fig. 2;

Fig. 5 is an end elevational view of the splint of Fig. 4;

Fig. 19 is a plan view of the foot hitch in applied position and

Fig. 20 is an elevational view of the foot hitch in applied position.

5 Referring now to the drawings, and particularly to Figs. 1 to 6 inclusive, I have shown my improved splint as comprising a pair of longitudinally adjustable members 10 and 11, having a pad element 12 secured to each of said members at one end and at the opposite end the members are secured to a cross-bar 13. The cross-bar 13 is preferably of tubular form and has a pair of rods 14 and 15 secured thereto by welding or the like. The rods 14 and 15 are provided 10 with transversely aligned perforations 16 spaced longitudinally along the rod at distances such as 15 4 inches. A pair of tubes 17 and 18 are telescoped over rods 14 and 15, the tubes 17 and 18 also being provided with spaced perforations 20 adapted to be aligned with perforations 16 in rods 14 and 15 whereby the tubes and the rods may be adjustably pin-connected.

I preferably employ a type of pin as illustrated in Figs. 8 and 9 wherein a pin 19 is riveted to a 25 pair of spring clips 20-20 and a reinforcing yoke 21. Thus the pin can be quickly projected through aligned perforations in the rods and tubes and locked by the spring clips 20 engaging the tube walls. To insure that the pins 19 will not become lost I preferably secure thereto one end of a wire or chain which may have its opposite end secured to the tube in any suitable manner.

30 The pad element 12 comprises a generally semi-circular ring suitably padded, the ring ends being reduced whereby they may be projected through the perforated ends of a pair of pins 24 and flanged to pivotally engage pins 24 with the ring ends. Pins 24 are circular in cross section and of a size to slide within tubes 17 and 18. Pivotally secured to pins 24 are pins 25 having substantially the same diameter as pins 24, the pins 25 being perforated as indicated at 26 whereby the element 12 may be secured to tubes 17 and 18 by projecting pins 19 through upper perforations 27 in the tubes, and perforations 26 of the pins. Element 12 will then project laterally from the members 10 and 11, and member 10 is preferably adjusted when supporting a fractured leg to a greater length than member 11 whereby the 45 padded member 12 may be comfortably adjusted to the inner side of the leg at the upper extremity and secured by a strap 28 which encircles pad element 12 and the upper part of the leg, the strap 28 preferably being provided with a friction type buckle for accurate adjustment. Strap 50 55 55 may be secured to pad element 12 by winding the pad material therearound.

Slideably mounted on one of the tubes, such as tube 17, are a plurality of straps 29 having preferably friction type buckles whereby the leg may be strapped to members 10 and 11 at spaced points for support. Any suitable means may be employed for mounting straps 29 on tube 18 but, as best illustrated in Figs. 10 and 11, I preferably provide a loop 30 at one end of the strap permitting the strap to be telescoped over the tube and slid therealong. Straps 29 when supporting an arm or leg are brought over tube 18 or rod 15 and around the tube or rod prior to passing over the top part of the leg or arm for buckling so that a supporting loop around tube 18 or rod 15 for the strap portion engaging the lower part of the arm or leg is effected. The buckles associated with straps 29 are generally indicated at 31 and may be of any conventional

form comprising a rectangular frame with a slideable friction cross-bar. However, since the splint may be used for either a right or left fractured member and preferably with the buckles disposed at the outer side of the member I provide a pivotal support for the buckles 31 as indicated at 32.

5 The pad element 12 is designed so as to dispose the members 10 and 11 laterally along each side of the leg in alignment with the main leg 10 bone where the greatest need for support occurs.

The bar 13 is adjusted to be disposed outwardly a substantial distance beyond the foot and is provided with a loop 13a through which a tensioning strap of a foot hitch generally indicated 15 at 70 may be projected. The tensioning strap will place the foot under tension to maintain the fractured ends of the bone separated during transportation of the injured person to a hospital or the like and prevent further injury as would 20 occur if the fractured bone portions were allowed to contact each other.

25 For supporting the leg out of contact with the floor, I provide a U-shaped member 35 having its ends pivoted to cross bar 13 whereby the member 35 may be quickly disposed in a position at right angles to members 10 and 11 to support the leg. The member 35 may have a flexible container 35a secured thereto serving as a storage space for the foot and hand hitches and like articles. Pins 19 are adapted to lock member 35 either in a position as indicated in Fig. 1 or generally parallel to rods 14 and 15 for storing.

30 The foot hitch 70 now will be described and this is best illustrated in Figs. 18, 19 and 20, the hitch 35 being designed so that the tensioning pull is transmitted primarily to the heel so that there is no tendency to cut off circulation of blood in the lower part of the foot. The hitch comprises a pair of cross-straps 36 and 37 secured together by stitching or the like, strap 36 being provided with a buckle 38 and a cooperating strap 39, and strap 37 being provided with a buckle 40 and a cooperating strap 41.

35 Referring to Figs. 19 and 20 it will be noted that the secured portions of straps 37 and 36, generally indicated at 43 are placed back of the heel and that part of strap 36 including strap 39, is passed over the top of the foot above the instep and that part of strap 37 including the buckle 40 is passed around the opposite side of the foot and over the top of the foot above the instep, the strap 39 then passing beneath the instep to engage buckle 40. The strap 42 will then be disposed in loop form outwardly from the foot and is grasped with one hand to exert outward tension on the foot until the strap 41 is passed through loop 13a and secured to buckle 38. Buckle 38 and strap 41 are passed inside of the loop buckled around the instep. It will be noted that the tension is primarily applied back of the heel and although there may be a slight tendency to exert pressure on the instep and the top of the foot, this is not sufficient to affect the blood circulation through the lower part of the foot to any appreciable degree. It will also be noted that loop 13a is disposed generally centrally along the foot and that the pull exerted by the tensioning strap 41 is exerted equally on each side of the foot so there is no tendency to twist the foot from a natural position.

40 Referring now to Figs. 2 and 4, I have shown the splint as adapted to support a fractured arm and in this case the members 10 and 11 are preferably adjusted to an equal length and the pad 75

element is disposed in a manner to be suspended generally parallel to members 10 and 11. In this case the pins 24 pivoted to ring 23 of member 12, are rotated through 90° from the position illustrated in Figs. 13 and 14 with pins 25 telescoped within the upper ends of tubes 17 and 18 and locked therewith by inserting pins 19 through perforations 40 in the tubes and perforations 26 in pins 25. Thus, pad element 12 may be disposed under the arm pit with the members 10 and 11 extending laterally outwardly therefrom to overlie and underlie the main bones of the arm in alignment with the shoulder joint. In other words, support members 10 and 11 are applied at a plane at right angles to the plane in which the fore-arm is bent at the elbow rather than in the plane of the bending of the fore-arm, since this is the plane in which the greatest support is needed.

20 Straps 29 then encircle members 10 and 11 and the arm and are buckled to secure the splint firmly to the arm. Tension will be applied to the arm at the wrist by a hand hitch which will now be described.

25 The hand hitch 50 is illustrated in plan view in Fig. 15 and comprises a generally U-shaped element of flexible material including arm portions 51 and 52 and a yoke portion 53. Secured to the inner side of yoke portion 53 is a buckle 55 and strap 56 secured to the arm portions 51 and 52 is a rigid padded hand grip 57. A buckle 59 and a strap 60 are secured to the hand grip 57. A strap 61 is secured to arm portions 51 and a buckle 62 to arm portion 52. 30 A grip strap 58 is also secured to the hand grip.

The manner of securing the hitch to the wrist and hand will now be described in connection with Figs. 16 and 17. The hand is inserted beneath the hand grip 57 palm up so that the palm 40 may engage the hand grip and the yoke portion 53 encircles the wrist through linking strap 56 through buckle 55. The portion of strap 51 adjacent the wrist will engage the side of the hand and part of the back of the hand and be brought 45 around angularly over the clenched fingers permitting strap 61 to encircle the under side of the wrist. Portion 52 adjacent the wrist is brought along the opposite side of the hand and partially along the back of the hand and will criss-cross the portion 51 at the finger tips permitting buckle 55 50 to encircle the underside of the wrist whereby strap 61 may be looped through buckle 62 so that the clenched hand is engaged by the crossed portions 51 and 52 while the wrist is engaged by the portion 53. The criss-crossed portions 51 and 52 are projected through the loop 55 which may be grasped to direct an outward pull on the hand or away from the shoulder to permit strap 60 to be projected through loop 13a and engage the buckle 59. Inasmuch as both the grip strap 58 and the tensioning strap and buckle are secured to the hand grip, the tendency will be to transmit strain through the fingers primarily and then to the wrist. Also, since 60 both sides of the hand are supported by portions 51 and 52, and the pull at all times is directed outwardly, there is no tendency to twist the hand which might aggravate the injury. Further, the pull is directed from the median line of the main bones of the arm extending from the shoulder so that there is no twisting tendency in this respect.

Both the foot hitch and the hand hitch can be quickly applied and the tensioning straps in both cases are sufficiently long to care for any

additional adjustment required after approximately adjustment has been made through movement of tubes 17 and 18 relative to rods 14 and 15. Further, the straps which secure the hitch to the foot or hand are sufficiently long so that a foot or hand of any size can be easily accommodated. I contemplate that a registering device for indicating the tension applied to an arm or leg may be associated with the tensioning straps or loop 13a.

10 The parts of the splint other than padding for element 12, the straps 29, and the hitches are preferably formed of aluminum alloy sufficiently pure to permit X-ray pictures to be taken at the hospital without disturbing the emergency 15 setting of the injured member at the scene of the accident and prior to careful setting of the fractured bone portions. It is found that aluminum or aluminum alloy of this type are sufficiently transparent for X-rays and cast only a 20 slight shadow and which does not interfere in any appreciable degree with a proper study of the injured bone portion. The splint is relatively compact and no additional equipment is required other than the hitches described.

25 Although I have shown and described a preferred form of my invention, I contemplate that numerous and extensive departures may be made therefrom without departing from the spirit of my invention or the scope of the appended 30 claims.

Having thus described my invention, what I claim is:

1. Hitch means adapted to be associated with a traction splint for applying tension to a fractured arm comprising a generally U-shaped piece of flexible material, a rigid hand grip secured to the U-arms at points spaced from the U-yoke, a flexible link element for encircling the wrist secured to the U-yoke, a flexible grip strap 40 secured to the hand grip, a tensioning strap and buckle secured to the hand grip, a buckle secured to one of the U-arms at its outer end, and a strap secured to the other U-arm at its outer end.

45 2. Hitch means adapted to be associated with a traction splint for exerting tension on a fractured leg, comprising a pair of crossed strips of flexible material secured together generally centrally of the strips, a flexible grip secured to one end of each of the strips, a buckle secured to an end of one strip, a strap secured to the other end of said strip, a strap secured to an end of the other strip and a buckle secured to the opposite end of the other strip.

55 3. Hitch means adapted to be associated with a traction splint for applying tension to a fractured extremity comprising an element of flexible material, a flexible grip strap secured at its ends to said element, a buckle secured to said element, and a strap portion extending from said element and adapted to be received in said buckle.

65 4. Hitch means adapted to be associated with a traction splint for applying tension to a fractured arm comprising a generally U-shaped piece of flexible material, a rigid hand grip secured to the U-arms at points spaced from the U-yoke, a flexible link element for encircling the wrist secured to the U-yoke, flexible means and tensioning means secured to the hand grip, fastening means secured to one of the U-arms at its outer end adapted to be secured to the outer end of the other U-arm.

70 5. Hitch means adapted to be associated with

a traction splint for exerting tension on a fractured leg, comprising a pair of crossed strips of flexible material secured together generally centrally of the strips, a flexible grip secured to one end of each of the strips, fastening means secured to an end of one strip adapted to be secured to the other end of said strip, fastening means secured to the opposite end of the other strip adapted to secure the opposite end of said first strip.

6. Hitch means adapted to be associated with a traction splint for applying tension to a fractured extremity comprising an element of flexible material, a flexible grip strap secured at its ends to said element, fastening means secured to said element, and a strap portion extending from said element and adapted to be secured to said fastening means.

EDGAR ELLIS.
